(57) **CLAIM**

The ornamental design for a blood pressure monitor, as shown and described.

DESCRIPTION

FIG. 1 is a front perspective view of a blood pressure monitor showing our new design.

FIG. 2 is a front view thereof.

FIG. 3 is a rear view thereof.

FIG. 4 is a left side view thereof.

FIG. 5 is a right side view thereof.

FIG. 6 is a top view of thereof.

FIG. 7 is a bottom view thereof; and,

FIG. 8 is another perspective view thereof, shown in a use state.

The broken lines in the strap and monitor depict portions of the blood pressure monitor that form no part of the claimed design, and the broken lines representing human hand and arm in FIG. 8 depict environment only and form no part of the claimed design.

1 Claim, 8 Drawing Sheets
